CUTTER TOOL LOCKING MECHANISM

James A. Anania, Newark, N. J.

Application January 18, 1945, Serial No. 573,380

2 Claims. (Cl. 29—48)

This invention relates to an improved cutter tool locking mechanism, being especially designed for use in connection with the cutter tool assembly disclosed in my copending application filed October 11, 1943, Serial Number 505,859.

In my improved cutter tool assembly mentioned, a tool holder is provided with a rotatable cutter head having circumferentially spaced cutters thereon and it is therefore necessary to lock the head in rotatably adjusted position in order to render the several cutters selectively active. Set bolts and other locking means have been tried for the purpose but have not proven entirely satisfactory. A sliding, spring-retracted locking pin has also been tried but it has been found that unless the pin is provided with a rigid axial abutment, looseness will develop between the pin and head while the tool assembly is in use.

It is accordingly an object of the present invention to provide a locking mechanism wherein a sliding, spring-retracted locking pin for the cutter head will be provided with a rigid axial abutment.

A further object of the invention is to provide a locking mechanism wherein the locking pin will be solidly supported at both ends thereof, and wherein the bushing employed for supporting the forward end of said pin may be adjusted toward the forward working terminal of the pin to afford added rigidity thereto.

And a still further object of the invention is to provide a locking mechanism embodying an axially disposed abutment rod for the locking pin, wherein said rod will provide a rigid stop behind said pin, wherein the rod may be manually adjusted for projecting the pin into engagement with the cutter head or to permit the retraction of the pin, and wherein the rod will be solidly supported at both ends thereof so as to prevent any slight buckling or bending of the rod under end thrust of the locking pin thereon.

Other and incidental objects of the invention will appear during the course of the following description, and in the drawing.

Figure 1 is a perspective view of my improved cutter tool assembly equipped with the present invention.

Figure 2 is a vertical, longitudinal sectional view more particularly showing the details of the present locking mechanism.

Figure 3 is a fragmentary, horizontal section on the line 3—3 of Figure 2.

Figure 4 is a transverse section on the line 4—4 of Figure 2.

In the drawing, I have shown my improved cutter tool assembly, previously identified,

equipped with the locking mechanism of the present invention. Briefly stated, said mechanism includes a tool holder having a shank 10 which is adjustable in the usual manner upon a tool post, as suggested in dotted lines in Figure 1, and formed on the shank is a fork 11. Rotatably adjustable between the arms of the fork is a cutter head 12 having a number of circumferentially spaced cutter rests 13 thereon, and seated upon said rests are removable cutters 14. In accordance with the present invention, the tip ends of the rests 13 are provided with sockets 15.

Formed through the shank 10 is a smooth, longitudinal bore 16, and screwed into the forward end of said bore is a bushing 17. Slidable through said bushing is a locking pin 18 on the rear end of which is formed a circular head 19, and disposed between said head and the bushing is a spring 20 for retracting said pin and normally holding the pin retracted.

The forward end of the pin 18 is engageable in the sockets 15 of the cutter head 12 selectively and the head 19 is formed to snugly but slidably fit in the bore 16 so that the head will solidly support the rear end of the pin while the bushing 17 will solidly support the pin at its forward end portion. Furthermore, as will be observed, the bushing 17 may be adjusted forwardly in the bore 16 so that the forward terminal of the bushing will lie closer to the forward terminal of the pin for affording added rigidity to the free end of the pin.

Screwed into the bore 16 of the shank 10 at the rear end of said bore is a bushing 21, and screwed through said bushing is an abutment rod 22 disposed axially of the locking pin 18. At its forward end, the rod 22 is provided with a circular head 23 which snugly but slidably as well as rotatably fits in the bore 16 of the shank 10 for solidly supporting the forward end of the rod while the bushing 21 will solidly support the rod at its rear end portion. Thus, any slight buckling or bending of the rod under end thrust of the locking pin 18 thereon will be prevented.

The head 23 of the rod 22 seats flat against the head 19 of the locking pin 18 to provide a stop therefor, and pinned or otherwise removably secured upon the rear end of said rod is a knob 24. Accordingly, as will be seen, the rod 22 may be manually adjusted forwardly when the head 23 of the rod will rotate against the head 19 of the locking pin 18 and project the pin into one of the sockets 15 of the cutter head 12. A rigid and solid lock for the head is thus provided, and preferably, the rod 22 is equipped with a lock nut

25. Upon counter-rotation of the rod 22, the locking pin 18 will, of course, follow the rod under the action of the spring 20 so that the locking pin will be retracted to free the cutter head.

Having thus described my invention, what I claim is:

1. In a cutter tool locking mechanism, the combination of a tool holder having a shank, a cutter head rotatably adjustable upon the holder, a locking pin freely slideable upon the shank and movable forwardly to engage at its forward end with the head and lock the head in adjusted position, and an abutment rod connecting the rear end of said pin to extend axially thereof and rotatably adjustable upon the shank for shifting said pin forwardly.

2. In a cutter tool locking mechanism, the com-

bination of a tool holder having a shank provided with a bore therethrough, a cutter head rotatably adjustable upon the holder, a bushing mounted in the forward end of said bore, a locking pin 10 slideable through said bushing and provided at its rear end with a head slidably fitting in said bore, a spring disposed between said head and bushing and acting to retract the pin, a second bushing mounted in the rear end of said bore, and an abutment rod screwed through the latter bushing and provided at its forward end with a head rotatably fitting in said bore to contact the head of said pin, said rod being rotatably adjustable for sliding the pin forwardly to engage and lock the head in adjusted position.

JAMES A. ANANIA.
